INJECTOR

Joseph F. Griffin, Teaneck, N. J., assignor to The
Superheater Company, New York, N. Y.

Application June 7, 1932, Serial No. 615,855

8 Claims. (Cl. 103—265)

The present invention relates to injectors and has particular reference to injectors of the type provided with fluid pressure actuated control systems. More particularly the invention relates to water valve actuating mechanism and still more particularly, the invention relates to water valve actuating mechanism for exhaust steam injectors.

In many forms of injector control systems as heretofore employed, the water valve of the injector is opened by means of a fluid pressure actuated piston in communication with a source of high pressure steam. In the forms of apparatus heretofore employed, the valve operating piston has been mounted in a suitable chamber in the injector body and has operated a valve stem or plunger to open the water valve. In order to prevent leakage of steam around the actuating piston to the water space of the injector, such pistons have heretofore been provided with seats engaging a part of the injector body to prevent such leakage and further precaution has been taken by the provision of a vent between the seat and the water space of the injector through which steam can leak to atmosphere in case a seat is not steam tight.

With the arrangements hitherto employed, numerous practical operating difficulties have been found to exist. Thus, for example, leakage of water frequently occurs due to a worn or badly fitted stem or plunger for operating the water valve and such leakage has led to serious damage to the actuating mechanism, particularly in the case of locomotive injectors in which in many instances water which has leaked into the chamber for the actuating piston has frozen when the injector was not in operation. Freezing of water in this part of the apparatus has not only rendered it inoperative but has also in many instances cracked the injector body and necessitated the replacement of the entire body of the injector.

It is the general object of the present invention to provide an improved form of valve operating mechanism particularly for water valves which will eliminate the difficulties heretofore encountered.

The nature of the invention and the more detailed objects thereof will be more fully set forth in the ensuing description of a preferred embodiment illustrated in the accompanying drawing, in which,

Fig. 1 is a section taken on the line 1—1 of Fig. 2 and showing part of an exhaust steam in-

jector having a water valve operating mechanism embodying the invention and

Fig. 2 is a half section taken on the line 2—2 of Fig. 1.

Referring now to the drawing, 10 designates the injector body in which is mounted the main steam nozzle 11 and the water nozzle 12.

In the specific form of injector illustrated, which is of the exhaust steam type, low pressure steam is admitted to the chamber 13. This steam may be either exhaust steam admitted through valve 14 or it may be auxiliary live steam at low pressure admitted through conduit 15 to the chamber 16, the latter communicating with chamber 13 by way of ports 17. Supplementary high pressure steam is admitted through conduit 18 to the chamber 19 which is in communication with the high pressure steam nozzle 20.

The body of the injector provides a water space 21 which it will be observed is in communication with the water nozzle 12. The admission of water to space 21 is controlled by water valve 22, water being admitted to this valve through conduit 23. Valve 22 is of the poppet type and seats, as shown, in the direction of water flow to the injector and is advantageously loaded by means of a light spring 24.

The valve actuating mechanism for opening valve 22 comprises a casing 25 detachably secured to the body 10 as by means of bolts 26 and projecting into the water space 21. It will be observed that this casing when in position forms in effect a part of the injector body.

Casing 25 has a bore therethrough comprising a portion 27 of relatively large diameter and a portion 28 of smaller diameter. The portion 28 provides a guide for a plunger element 29 having an enlarged portion or head 30 adapted to seat against a seat 31 provided by the shoulder at the outer end of the portion 28 of the bore. A piston 32 is slidably mounted in a large diameter portion 27 of the bore and is adapted to engage a seat 33 provided at the end of this portion of the bore. Piston 32 is guided by means of a stem 34 which is slidably mounted in a suitable recess 35 in plunger 29 and is advantageously further guided by a downwardly projecting stem 36 passing through an apertured web 37 in cap 38 which provides a closure for the bottom of casing 25. A spring 39 is located around stem 34 between piston 32 and the head 30 of the plunger 29.

A vent 40 leading to atmosphere or other zone of low pressure is provided in the wall of the casing 25 and communicates with the bore in the casing between the spaced seats 31 and 33. The

105

110

upper end of the cap 38 provides a stop for piston 32 and a passage 41 serves to connect the space below the piston with the chamber 19 to which high pressure supplementary steam is admitted.

5 The operation of the apparatus is as follows:

When the injector is not in operation, the apparatus assumes the position shown in Fig. 1 with the water valve 22 seated due to the action of spring 24 and also due to the static head of water

10 acting on the valve in case the supply tank to which conduit 23 is attached is at a level higher than the level of the injector. It will be appreciated that if desired, the spring 24 may be omitted, particularly in installations where a con-

15 siderable static hydraulic head is normally exerted on valve 22. With the injector not in operation no pressure is exerted below piston 32 and this piston, the plunger 29 and the associated spring drop to the position shown due to gravity.

20 In case the mechanism is placed in a horizontal position rather than in a vertical position as shown, a suitable retracting spring may be employed if desired.

When operation of the injector is started, steam 25 is admitted through supply pipe 18 and passes through passage 41 to the space below piston 32, lifting this piston and the plunger 29. Spring 39 is sufficiently stronger than spring 24 to over-

30 balance the static hydraulic head on valve 22 so that when the plunger 29 is moved upwardly, due to movement of piston 32 and through the medium of spring 39, into contact with valve 22, the valve is opened against the forces tending to seat it. Piston 32 and plunger 29 move upwardly 35 without relative movement until contact is made between the plunger and the valve and this movement is continued until the head of plunger 29 seats against seat 31. As will be observed from the drawing, the normal unstressed length of 40 spring 39 is greater than the distance between seats 31 and 33 so that when the plunger seats the piston 32 is still unseated. Piston 32 continues its upward movement after the seating of plunger 29, until it seats against seat 33. This 45 continued movement of the piston is possible due to the resilience afforded by spring 39.

With the parts in operative position when the injector is in operation, steam leakage past piston 32, which advantageously is not a steam tight fit 50 in the bore 27, is prevented by the seating of the piston against seat 33. Likewise, leakage of water through the portion 28 of the bore around the plunger 29 is prevented by the seating of head 30 against seat 31. As will be observed from 55 the drawing, the head 30 of plunger 29 passes the point where vent passage 40 communicates with the bore before it reaches its seat. Thus this vent passage communicates with the bore at a point which permits the vent to discharge 60 any steam which may leak past the seat 33 due to wear or other imperfection in the seat and to also discharge water which may pass seat 31 in case of an imperfect fit at this point.

Particularly in the case of exhaust steam injectors, it is highly important that the temperature of the water reaching the water nozzle be as low as possible and leakage of water valve operating steam into the water space ahead of the nozzle should be particularly guarded against. 65 The present construction provides complete protection against leakage because of the two seats 33 and 31 which steam would have to pass before it could reach chamber 21, even if the vent 40 became clogged. Likewise, the leakage of water into the valve operating casing is guarded against

80 by structure providing a double seat. The resilient connection between piston 32 and plunger 29 insures proper seating of both of these members against their respective seats and eliminates the difficulties of maintaining the two parts in proper simultaneous engagement with their seats which would be encountered if the two parts were rigidly connected to each other.

85 If for any reason water should find its way into the casing 25 and damage it due to freezing, the arrangement shown permits the ready removal and replacement of the damaged parts without interfering in any way with the rest of the injector structure.

90 A drain cock 42 may advantageously be provided to enable the small quantity of moisture to be drained from cap 38 which may collect therein due to condensation of operating steam below piston 32.

95 While the invention has been illustrated as applied to one specific type of injector, it will be apparent that the invention is not limited in its application to the type of injector which has been chosen for purposes of illustration but may equally well be applied to other types of injectors. It 100 will also be evident that the specific valve operating structure which has been illustrated may be modified in various ways without departing from the invention.

105 What I claim is:

1. In an injector having a water nozzle, an injector body providing a water space in communication with said nozzle, said body comprising a wall having a bore therethrough communicating with said space, a valve for admitting water to 110 said space and means for opening said valve comprising a fluid pressure actuated piston seating against a portion of said wall to prevent leakage of actuating fluid past the piston when the valve is open, and an intermediate element slidably mounted in said bore and actuated by said piston to open said valve, said intermediate element seating at the outer end of said bore when the valve is open to prevent leakage of water from said space to the space in which said piston 120 operates.

2. In an injector having a water nozzle, an injector body providing a water space in communication with said nozzle, said body comprising a wall having a bore therethrough communicating 125 with said space and a valve seat at the outer end of the bore and means for opening said valve comprising an element having a portion slidably mounted in said bore and a head having a face adapted to engage said seat when the valve is open, a fluid actuated piston and a spring interposed between said piston and said element for transmitting motion from the piston to the element, said spring acting to seat said element and to maintain it in seated position when the piston 130 is actuated to open the valve.

3. In an injector having a water nozzle, an injector body providing a water space in communication with said nozzle, said body comprising a walled portion providing an inlet for admitting water to said space and a wall portion opposite said inlet having a bore therethrough and a valve seat at the outer end of the bore, a poppet valve for controlling said inlet, a plunger slidably mounted in said bore and having a head engaging said seat to prevent leakage of water through said bore to the exterior of said space when the valve is open, a fluid actuated piston, and a spring interposed between said piston and the head of said plunger for seating the plunger and main- 145 150

- taining it in seated position when the piston is actuated.
4. In an injector having a water nozzle, an injector body providing a water space in communication with said nozzle, said body comprising a wall portion having a differential bore therethrough, said bore having an inner portion of relatively small diameter, an outer portion of relatively large diameter and an intermediate portion of intermediate diameter, and there being valve seats between the portions of different diameter, a valve for admitting water to said space, a plunger slidably mounted in the portion of said bore of relatively small diameter, said plunger being adapted to open said valve and having a head adapted to engage the seat between the portion of the bore of relatively small diameter and the portion of the bore of intermediate diameter, a fluid pressure actuated piston located in the portion of the bore of relatively large diameter, said piston being adapted to engage the seat between the portion of the bore of intermediate diameter and the portion of the bore of relatively large diameter, and a spring between said piston and said element for transmitting motion from the piston to the element and for maintaining the element in seated position when the piston is moved to engage its seat.
5. In an injector having a water nozzle, an injector body providing a water space in communication with said nozzle, said body comprising a wall portion having a differential bore therethrough, said bore having an inner portion of relatively small diameter, an outer portion of relatively large diameter and an intermediate portion of intermediate diameter, and there being valve seats between the portions of different diameter, a valve for admitting water to said space, a plunger slidably mounted in the portion of said bore of relatively small diameter, said plunger being adapted to open said valve and having a head adapted to engage the seat between the portion of the bore of relatively small diameter and the portion of the bore of intermediate diameter, a fluid pressure actuated piston located in the portion of the bore of relatively large diameter, said piston being adapted to engage the seat between the portion of the bore of intermediate diameter and the portion of the bore of relatively large diameter, and a spring between said piston and said element for transmitting motion from the piston to the element and for maintaining the element in seated position when the piston is moved to engage its seat.
6. In an exhaust steam injector having a body and a water valve seating in said body, means for opening said valve comprising a casing detachably secured to said body, said casing having a differential bore comprising a portion of relatively small diameter, a portion of relatively large diameter and an intermediate portion of intermediate diameter, a valve actuating plunger mounted in the portion of relatively small diameter, said plunger having a head adapted to engage a seat in said casing between the portion of the bore of relatively small diameter and the portion of the bore of intermediate diameter, a piston mounted in the portion of the bore of relatively large diameter, said piston being adapted to engage the seat between the portion of the bore of relatively large diameter and the portion of the bore of intermediate diameter, means for admitting pressure fluid to the portion of the bore of relatively large diameter to move said piston to its seat and a spring between said piston and said plunger for moving the latter to its seat when the piston is seated.
7. Water valve operating mechanism for injectors comprising a casing adapted to be detachably secured to an injector body, said casing having a bore therethrough having portions of different diameter, a piston mounted in a portion of larger diameter, a plunger adapted to contact a valve part and mounted in a portion of smaller diameter, and a spring between said piston and said plunger, said portions of said bore providing two axially spaced seats, one of said seats being at the end of said portion of the bore of smaller diameter, said plunger being adapted to engage the seat at the end of the portion of the bore of smaller diameter to prevent leakage of fluid into said casing, and said piston being adapted to engage the other of said seats to prevent leakage of actuating fluid past the piston.
8. In an injector having a water nozzle, an injector body providing a water space in communication with said nozzle, said body comprising a wall having an opening for admitting water to said space and a separable casing detachably secured to the main portion of the body opposite said opening, a water valve of the poppet type for controlling the flow of water through said opening and fluid pressure actuated means for opening said valve located in said casing and comprising a fluid pressure actuated piston and an element actuated by said piston for opening the valve, said element being separate from and movable relative to said piston and comprising a portion seating against the wall of the casing to prevent leakage of water from the water space of the injector to the interior of the casing.
